CAKE OR BISCUIT.

No. 13,140.

Patented Aug. 8, 1882.

UNITED STATES PATENT OFFICE.

FREDRICK G. CASS, OF CAMBRIDGEPORT, MASSACHUSETTS.

DESIGN FOR A CAKE OR BISCUIT.

SPECIFICATION forming part of Design No. 13,140, dated August 8, 1882.

Application filed June 27, 1882. Term of patent 3½ years.

To all whom it may concern:

Be it known that I, FREDRICK G. CASS, a citizen of the United States, residing at Cambridgeport, in the county of Middlesex and State of Massachusetts, have invented and produced a new and original Design for Cakes, Biscuits, Crackers, &c., of which the following is a specification, reference being had to the accompanying photograph, forming part there-
of.

The leading feature of my design consists in a cake, biscuit, or cracker, A, made in the form and likeness of P. T. Barnum, the great showman, as represented in the photograph; the design thus produced being unique and ornamental. Upon the surface of the said cake, biscuit, or cracker is stamped the name "Barnum;" but the initials "P. T. B." may be substituted for the word "Barnum," or the said

word or initials may be omitted, if desired, 20 without altering the character of my design.

What I claim as my invention, and desire to secure by Letters Patent, is—

1. The design for cakes, biscuits, crackers, &c., the same consisting of the form and likeness of P. T. Barnum, substantially as herein shown and described.

2. The design for cakes, biscuits, and crackers, the same consisting of the form and likeness of P. T. Barnum, in combination with the 30 word "Barnum," substantially as herein set forth.

Witness my hand this 23d day of June, A. D. 1882.

FREDRICK G. CASS.

In presence of—

P. E. TESCHEMACHER,
W. J. CAMBRIDGE.
